UNITED STATES PATENT OFFICE.

WILLIAM R. BAKER, OF CHICAGO, ILLINOIS, ASSIGNOR TO THE McCORMICK HARVESTING MACHINE COMPANY, OF SAME PLACE.

BUNDLE-CARRIER FOR AUTOMATIC GRAIN-BINDERS.

SPECIFICATION forming part of Letters Patent No. 361,976, dated April 26, 1887.

Application filed August 8, 1884. Serial No. 140,022. (No model.) Patented in England July 19, 1884, No. 10,330.

To all whom it may concern:

Be it known that I, WILLIAM R. BAKER, of Chicago, in the county of Cook and State of Illinois, have invented certain new and useful 5 Improvements in Bundle-Carriers for Automatic Grain-Binders, of which the following is a specification.

In order to save labor to the shockers in collecting and assembling individual sheaves discharged from the binder after each distinct binding operation, receptacles or bundle-carriers have of late years been attached to the machine to receive and carry the sheaves as they drop fully bound until a sufficient number have accumulated to form a shock, when the receptacle is opened and all deposited on the ground in a lump. Usually the entire labor of opening the receptacle has fallen upon the driver or attendant, unduly taxing his attention and strength.

My invention has for its object to accomplish this by a friction connection with the harvester-gearing, readily thrown into operation by the driver; and it consists in combining with a hinged gravitating bundle-carrier a rope or band leading therefrom to a friction-drum on the harvester, a constantly-driven friction-disk arranged for engagement with said drum, and a lever controlled by the driver, whereby such engagement is caused at will; in combining with a hinged gravitating bundle-carrier a rope or band leading therefrom to a friction-drum on the harvester, a constantly-driven friction-disk arranged for engagement with said drum, a lever controlled by the driver, whereby such engagement is caused at will, a stop upon the band, and a check arm or yoke upon the frame, against which said stop strikes when the carrier is fully open, thereby sufficiently breaking the connection between the drum and friction-disk to leave the carrier stationary until the sheaves are discharged and the driver releases his lever; in such combinations and details as are herein-after more particularly pointed out and claimed.

In the drawings, Figure 1 is a rear elevation of so much of a harvester and binding table, 50 in connection with my improvement, as is nec-

essary to an explanation thereof. Fig. 2 is an elevation from the stubble end of the machine. Fig. 3 is an enlarged detail of the friction-gearing and certain accessories, as shown in the previous figures. Fig. 4 is a vertical longitudinal section, Fig. 5 is an end elevation, and Fig. 6 is a top view, of the preferred form of said gearing. Fig. 7 is a detail thereof.

A represents the elevator-frame, of usual shape; B, the driver's seat mounted on a plank 60 inside the elevator, or where otherwise required by the exigencies of the machine; and D is the binding-table. The automatic binding mechanism customarily employed in connection with such table is not shown; but it 65 will be understood that the operation of my improvement has no relation to any particular form or type of binder or binding-table.

Two supporting-frames, formed of crossed bars E E', are bolted, one to the front rail and 70 sill and the other to the rear rail and sill of the elevator-frame. To the lower bars of these two frames, immediately beneath the tail-board of the binding-receptacle, is secured a board, F, forming the inner member of the bundle-75 receptacle. This board is attached by means of pivots or hinges under such arrangement that a rule-joint is formed, whereby said hinges permit it to fall to a sloping position, but hold it rigidly against further descent, that it may 80 form a bundle-chute to direct the sheaves easily upon the carrier.

The bundle-carrier proper, G, is composed of an open frame-work of bars and slats secured together by cross-pieces or ties, which will 85 visibly be of metal. It is hung from the upper bars of the cross-pieces by means of bails g g', which take into notches in the outer ends of said bars, and are secured therein by hooks or latches, or otherwise. From the outer side 90 of the swinging carrier rises a long lever-arm, H, the top of which is brought substantially in line with the rear of the elevator and almost on a level with the head of the elevator at that point. By means of this lever the 95 carrier can be swung back upon its supports; but when the lever is released said carrier will gravitate until its inner side closes beneath and against the edge of the above-mentioned hinged board, and as it continues to close lifts 100

said board slightly, so that a close joint may be established from the moment said inner side meets the edge of the board and before the carrier is fully closed.

5 The pinion I on the rear gudgeon of the upper elevator-roller drives an idler, i, which communicates motion to a spur and friction gear, i', mounted loosely upon a short spindle supported in brackets on the top bar of the 10 elevator-frame. On the same spindle and alongside of the friction-gear is loosely mounted a drum, K, having a limited motion longitudinally of the spindle. On the spindle, at the end away from the pinion, is also mounted a 15 thimble, K', which, after encircling the spindle close to the hub of the friction-drum, bridges the adjacent bracket standard and caps, and is steadied by the protruding end of the spindle. Between the drum-hub and the thimble a 20 washer may be inserted. The thimble does not fit close on each side of the standard which it bridges, but is allowed a limited play longitudinally of the spindle, notwithstanding the bridge. Against the cap on this thimble 25 presses one end of a crank-lever, k, pivoted in a sleeve, k', from the bracket supporting the drum, and depending diagonally along the inner rear strut of the elevator to a position near the standard of the driver's seat, where 30 its lower end is connected by a strap or link with the treadle L convenient for operation by the driver. Thus when the driver presses upon the treadle, or with his heel presses upon the strap between the treadle and lever, the 35 friction-drum will be caused to engage with its corresponding gear, which is continually driven from the elevator-roll, and the drum will be driven by the friction-grip ensuing between the two. As a modification, the thimble 40 may be omitted and the end of the lever caused to yoke with a groove or recess in the hub of the drum, as indicated in Fig. 3. In such case the lever may be straight and the position and character of its pivot somewhat 45 altered, as shown.

To the upper end of the lever, on the bundle-carrier, is attached one end of a rope or cord, M, the other end being wound upon the drum, so that when the drum is engaged with 50 its friction-gear and revolving this cord will be taken in and the lever operated to open the carrier.

Near to the drum is placed a guide or check yoke, through which the cord passes, and upon 55 the cord is adjusted a block, so that when sufficient of the cord has been wound up upon the drum to open the bundle-carrier to its full extent this block comes against the stop or check yoke and prevents a further length being wound, as the friction-grip between the drum and gear will be overcome sufficiently to permit the gear to revolve while the drum remains stationary, holding the cord, and thereby the carrier, open until all the sheaves have been 60 discharged, when the driver, releasing his pressure on the foot treadle or strap, will re-

lease the drum from further frictional contact with the gear, and the gravity of the carrier will unwind the cord and close the receptacle.

Instead of the direct connection of the rope or cord with the top of the lever, a sheave may be mounted on said lever and the rope led from the drum over the sheave and then returned, and its free end fastened to the drum-bracket or to an eye thereon, or near thereto, thus decreasing the labor on the drum and opening the carrier with less violence.

The cross-frames which support the swinging carrier are adopted as a convenience, and because they afford a simple, strong, and efficient means of attaching and suspending the carrier from the ordinary harvester-frame without any structural changes in that frame. I do not intend, however, to be limited to these precise means for the support of the carrier, although considering them the simplest and most efficient. Nor do I intend to be limited to a carrier of the precise shape shown so far as my improvement relates to operating the bundle-carrier by means of a friction connection with the harvester-gearing, nor to the specific friction connection described, as there are several well-known forms of friction-clutch.

I claim as my invention—

1. The combination, with the hinged gravitating bundle-carrier, of the rope or band leading therefrom to a friction-drum on the harvester, a driven gear or disk arranged for frictional engagement with said drum, and a lever controlled by the driver, whereby such engagement is caused at will.

2. In combination with the hinged gravitating bundle-carrier, a rope or band leading therefrom to a friction-drum on the harvester, a driven gear or disk arranged for frictional engagement with said drum, a lever controlled by the driver, whereby such engagement is caused at will, a stop upon the band, and a check arm or yoke upon the frame, against which said stop strikes when the carrier is fully open to overcome the frictional engagement between the drum and gear.

3. The combination, substantially as herein-before set forth, of the gravitating bundle-carrier, its lever-arm, the spur and friction gear driven from the pinion on the upper elevator-roller, a friction-drum on the same spindle as said friction-gear, a lever arranged to press said drum longitudinally of the spindle and into engagement with the gear, and the rope or band connecting the drum with the lever on the bundle-carrier.

4. The combination, with the binding-receptacle, of the hinged gravitating board or bundle-chute sloping outward from beneath the tail of said receptacle, and checked against further descent in such sloping position, while free to rise therefrom, and the gravitating bundle-carrier arranged in such manner that as it closes its inner end passes beneath the edge of said board and lifts it slightly.

5. The combination of the cross-frames bolted to the front and rear rails and sills, the inclined board hinged to the lower members of the respective cross-frames, and the bundle-
5 carrier slung from the upper members of said frames.

6. The combination, substantially as herein-before set forth, of the hinged bundle-carrier, the driven friction-wheel, the friction-drum
10 mounted on the same shaft or spindle, the thimble encircling the shaft near the hub of the

drum, bridging the supporting-standard at that end and capping the outer end of the shaft, the lever bearing against the head or crown of the cap, and a connection between 15 the drum and the bundle-carrier, whereby the latter is tilted when the drum is set in motion.
